SUCTION NOZZLE

Fredrik Johan Robert Karlström, Stockholm,
Sweden, assignor to Electrolux Corporation,
Dover, Del., a corporation of Delaware

Application March 25, 1933, Serial No. 662,678
In Germany April 5, 1932

23 Claims. (CL 15—13)

My invention relates to the vacuum cleaning art and particularly to an improved suction nozzle.

The object of my invention is to provide a suction nozzle having an agitator member operated solely by the action of the air drawn through the nozzle and having no mechanical connection with the motor of the vacuum cleaner. In accordance with my invention I produce vibrations due to flow of air and preferably set up pulsations in the flow of air through the nozzle and mount an agitator member within the nozzle in such manner that it may be moved by the vibrations or pulsations.

Further objects and advantages of my invention will be apparent from the following description considered in connection with the accompanying drawings, which form a part of this specification and of which:

Fig. 1 is a plan view, partially in cross-section, of one embodiment of my invention;

Fig. 2 is a cross-sectional view taken on the line 2—2 of Fig. 1, and showing, in addition, the nozzle connected to a vacuum cleaner unit;

Fig. 3 is a cross-sectional view taken on the line 3—3 of Fig. 1;

Fig. 4 is a cross-sectional view taken on the line 4—4 of Fig. 1;

Fig. 5 is an elevational view of a portion of the nozzle shown in Fig. 2;

Fig. 6 is a cross-sectional view of another embodiment of my invention; and

Fig. 7 is a cross-sectional view of a third embodiment of my invention.

Referring more particularly to Figs. 1 to 5, reference character 10 designates generally a suction nozzle adapted to be connected by means of a rigid hollow handle member 11 and a flexible hose 12 or the like to a suitable source of suction, such as the vacuum cleaner unit 13, containing the usual dust bag, fan and motor (see, for example, U. S. Patent No. 1,860,885 to Bilde dated May 31, 1932).

Nozzle 10 comprises a casing formed by an upper part 14 and a lower part 15. The nozzle is elongated, as appears from Fig. 1, and the parts 14 and 15 are hinged together along one side by the hinges 16. The other side of the parts may be secured together by bolts 17 passing through openings in the part 14 and engaging threaded recesses in the part 15. The lower edges of part 15 define an elongated mouth or inlet opening or suction opening 18 which is adapted to be passed over the member or surface, such as a rug, which is to be cleaned. The edges

defining the inlet opening have grooves 19 formed therein, which grooves have a maximum depth at their inner ends and a minimum depth, which may be zero, at their outer ends.

Part 15 is formed with an inwardly extending flange 20. Secured to flange 20 by means of screws 21 is a strip of metal or the like 22, the inner edge of which is formed as an inverted U 23. A diaphragm 24 of flexible, and preferably though not necessarily resilient material, such as rubber, is formed with a ridge 25 around its outer edge and this ridge is adapted to be engaged by the inverted U portion 23 and clamped between it and the flange 20. Diaphragm 24 has an elongated shape corresponding to that of the nozzle 15 and has a similar, but smaller, elongated opening in the center thereof. The diaphragm is formed with a ridge 26 around its inner edge, which ridge is engaged by the U-shaped portion of a member 27. Member 27 is secured by screws 20 28 to a flange 29 formed on an agitator member 30.

Agitator member 30 comprises an elongated member having depending sides 31 connected by an arched portion 32 through the upper part 25 of which is formed an elongated opening 33. Resilient means, such as leaf springs 34, are secured to either end of agitator member 30 and to flange 20 of the casing. Springs 34 are adapted to support the agitator member within the casing so that the lower edge thereof is slightly above the plane of the inlet opening, as defined by the lower edges of the part 15. It will be noted that the diaphragm 24 and agitator member 30 divide the casing 10 into a lower chamber and an upper 35 chamber, communication between which is established through opening 33.

Upper part 14 of the casing 10 is formed with a hollow projecting portion 35 which is in part formed with a cylindrical outer surface. An outlet opening 36 extends through the cylindrical portion of projection 35. A coupling member 37 is pivotally secured to projection 35 by means of plates 38 and bolts 39. Coupling member 37 is formed in part with a cylindrical inner surface 45 which is adapted to engage the cylindrical outer surface of projection 35. Thus, the coupling member 37 and the rigid handle member 11 inserted therein may be pivoted about the nozzle 10 in order to use the nozzle under low furniture 50 without tilting the mouth-piece on the surface being cleaned. If desired, the construction may be such that, if the coupling member 37 is pivoted far enough, it will vary the effective size of the opening 36, or if pivoted still further, will un- 55

cover a portion of the opening 36 to the atmosphere, thus breaking the suction in the nozzle.

Secured within the upper part 14 of the nozzle by means of screws 40 is a pulsation member 41 comprising a piece of resilient material, preferably metallic, having its one end secured to the casing and its other end free and disposed across the lower open end of projection 35. Pulsation member 41 is so dimensioned and located that, when in unstressed condition, it substantially closes the lower end of hollow projection 35, but may be drawn into the projection whereupon the lower end of the outlet passage provided by the hollow projection is opened more or less.

15 The operation of this embodiment of my invention is as follows:

When the suction nozzle is connected to vacuum cleaner unit by means of the hollow handle 11 and hose 12, and the fan of the vacuum cleaner is operated, air is caused to flow into the lower chamber of the nozzle through the elongated inlet opening bounded by the edges 18, through the opening 33 in the agitator member 30 into the upper chamber and thence into the hollow projection 35 and through the outlet opening 36 into the coupling member 37 from whence the air passes through the handle 11 and hose 12 to the vacuum cleaner unit. If the mouth of the nozzle is passed over a dusty surface, this air will pick up and carry with it particles of dust, thus cleaning the surface.

In order for the air to pass into the hollow projection 35 it must deform the pulsation member to some position as is shown in dot and dash lines. In doing this the pulsation member is stressed while at the same time the air pressure tending to deform it is reduced, due to the increased size of the flow opening controlled by the pulsation member, whereupon the pulsation member springs back toward its unstressed position, thus again closing the flow opening. Thus the pulsation member vibrates back and forth in the air stream passing through the nozzle. This vibration sets up impulses in the air stream, which impulses act upon the diaphragm 24 to cause it to oscillate. This oscillation of the diaphragm causes the resiliently supported agitator member 30 to oscillate up and down, whereupon the agitator member strikes the surface being cleaned and thus dislodges dirt adhering thereto. The dirt thus dislodged is readily picked up by the air stream and carried to the dust separator in the cleaner 13.

In Fig. 6 there is shown a somewhat modified embodiment of my invention. In this embodiment the part 14 of the nozzle is formed with one or more auxiliary openings 45 through the top thereof. Pulsation member 41 is secured within the part 14 so as to be disposed in the path of air flow through the openings 45. The other parts of the nozzle are similar to those shown in Figs. 1 to 5, except that the construction of the diaphragm 24 and the means for securing it to the casing and the agitator have been modified. As is shown, the outer edge of the diaphragm is clamped directly between the upper part 14 and the lower part 15 of the nozzle, while the inner edge of the diaphragm is engaged within a slot formed in flange 29 of the agitator member 30. The agitator member is resiliently supported by springs 34 and is formed with an opening 33 therethrough.

In operation, the coupling member 37 is connected to a source of suction which draws air therethrough. This air is admitted into the nozzle

10 through the mouth defined by the lower edge 18 of the part 15 from whence it passes through the opening 33 in the agitator member into the upper chamber. Air is also drawn in through the auxiliary openings 45 and cause the pulsation member 41 to vibrate. This vibration causes pulsations in the air within the upper chamber, which pulsations cause the agitator member to oscillate up and down, thus striking the surface being cleaned and dislodging dust therefrom.

15 The nozzle shown in Fig. 6 is particularly well adapted for cleaning heavy carpets or the like which offer a large resistance to the flow of air into the mouth-piece opening. This resistance may be great enough to prevent sufficient flow of air to operate the pulsation member. In the nozzle shown in Fig. 6 the pulsation member is operated by a flow of air which is independent of the flow through the mouth-piece.

20 The nozzle shown in Fig. 7 is generally similar to that shown in Figs. 1 through 5 with the exception that additional auxiliary openings 46 are formed in the lower part 15 of the nozzle, and establish communication between the atmosphere and the lower chamber. Pulsation members 47 are secured within the nozzle in the path of flow of air through auxiliary openings 46.

25 This nozzle has the same advantages as that shown in Fig. 6, that is, that the air for operating the pulsation member or members is independent of the air flow through the suction opening. In addition, the air drawn into the auxiliary openings 46 passes into the lower chamber adjacent to the suction opening, thus causing turbulence therein and aiding in picking up dust from the surface being cleaned.

30 In addition to the pulsation members 47 there is shown in Fig. 7 a pulsation member 41 arranged in the same position as in Figs. 1 to 5. The reason for this is that, if the nozzle is used for cleaning rugs or material having a very loose weave offering but little resistance to the flow of air into the mouth piece, there may not be sufficient flow through the openings 46 to actuate the pulsation members 47. In this event, the large flow of air through the nozzle will actuate pulsation member 41. Hence, the nozzle shown in Fig. 7 may be used advantageously with rugs or the material to be cleaned which offers either a high or low or any intermediate resistance to the flow of air.

35 It is preferable that, in all of the modifications, the pulsation member be so chosen with respect to the diaphragm and agitator member that they will have similar periods of vibration so that the pulsation member and the agitator member will tend to vibrate or oscillate in phase with each other.

40 While I have disclosed my invention in connection with a suction nozzle adapted to be connected to the source of suction by means of a flexible hose or the like, it is obvious that my invention may be employed in connection with a nozzle which is integral with, or rigidly secured to, the rest of the vacuum cleaner. The embodiments herein described have been chosen for purpose of illustration only and are not to be considered as limiting the scope of my invention, which is to be determined by the appended claims viewed in the light of the prior art.

45 What I claim is:

50 1. A suction nozzle comprising a hollow member having an intake opening and an opening adapted to be connected to a source of suction, 75

an agitator member movably mounted with respect to said hollow member and movable due to variations of flow of air in said hollow member, and means separate from the agitator operative by flow of air through the hollow member for producing said variations of flow of air in said hollow member to cause movement of said agitator member.

2. A suction nozzle comprising a hollow member having an intake opening and an opening adapted to be connected to a source of suction, an agitator member movably mounted with respect to said hollow member and movable in a plurality of directions due to variations of flow of air flowing in one direction in said hollow member, and means separate from the agitator operative by flow of air through the hollow member for producing said variations of flow of air in said hollow member to cause movement of said agitator member.

3. A suction nozzle including a hollow member having an intake opening adapted to be connected to a source of suction, an agitator member movably mounted in said hollow member and movable due to variations of flow of air in said hollow member, and vibratory means separate from said agitator member operative by flow of air through the hollow member for producing said variations of flow of air in said hollow member to cause movement of said agitator member.

4. In a suction nozzle, a casing having an intake opening and having an opening adapted to be connected to a source of suction, means within said casing for causing varying air movement therein, and agitating means separate from the first-mentioned means in said casing adjacent to the intake opening operable by said varying air movement.

5. In a suction nozzle, a casing having an intake opening and having an opening adapted to be connected to a source of suction, means within said casing operable by flow of air therein for causing pulsations in said flow, and agitating means separate from the first-mentioned means in said casing adjacent to the intake opening operable by said pulsations.

6. In a suction nozzle, a casing having an intake opening and having an opening adapted to be connected to a source of suction, means within said casing operable by the flow of air therethrough for causing pulsations in said flow, and a separate agitator member movably mounted in said casing independent of the pulsation means and adjacent to the intake opening and arranged to move due to said pulsations.

7. In a suction nozzle, a casing having an intake opening and having an opening adapted to be connected to a source of suction, means in said casing for causing varying air movement therein, and a separate agitator member resiliently supported in said casing independently of the first-mentioned means adjacent to the intake opening and movable by said varying air movement.

8. In a suction nozzle, a casing having an intake opening and having an opening adapted to be connected to a source of suction, a pulsation member secured within said casing disposed in the path of air flow toward the last-mentioned opening, said member being resilient and arranged to be vibrated by said air flow to thereby cause pulsations in the flow, and agitating means in said casing mounted independently of said pulsation member adjacent to said intake opening operable by said pulsations.

9. In a suction nozzle, a casing having an in-

take opening and having an opening adapted to be connected to a source of suction, a pulsation member secured within said casing disposed in the path of air flow toward the last-mentioned opening, said member being resilient and arranged to be vibrated by said air flow to thereby cause pulsations in the flow, an agitator member, and means for mounting said member in said casing independently of the pulsation member and adjacent to said intake opening and so as to be movable in vertical direction only due to said pulsations.

10. In a suction nozzle, a casing having an intake opening and having an opening adapted to be connected to a source of suction, a pulsation member secured within said casing disposed in the path of air flow toward the last-mentioned opening, said member being resilient and arranged to be vibrated by said air flow to thereby cause pulsations in the flow, an agitator member, and means for resiliently supporting said member in said casing independently of said pulsation member and adjacent to the intake opening and movable in response to the pulsations.

11. In a suction nozzle, a casing having an intake opening and having an outlet opening adapted to be connected to a source of suction, a pulsation member secured within said casing disposed in the path of air flow toward said outlet opening, said member being resilient and arranged to be vibrated by said air flow to thereby cause pulsations in the flow, a flexible diaphragm secured in said casing and dividing the casing into a first chamber adjacent to said intake opening and a second chamber adjacent to said outlet opening, and an agitator member secured to said diaphragm and formed with an opening therethrough for the passage of air from said first chamber to said second chamber.

12. In a suction nozzle, a casing having an intake opening and having an outlet opening adapted to be connected to a source of suction, a pulsation member secured within said casing disposed in the path of air flow toward said outlet opening, said member being resilient and arranged to be vibrated by said air flow to thereby cause pulsations in the flow, an agitator member within said casing adjacent to said intake opening, resilient means for supporting said agitator member from said casing, and a flexible diaphragm between said agitator member and said casing dividing said casing into two chambers, said agitator member being formed with an opening therethrough for the passage of air from one chamber to the other.

13. In a suction nozzle, a casing having an intake opening and having an outlet passage adapted to be connected to a source of suction, a pulsation member comprising resilient material secured to said casing and, in unstressed condition, substantially closing said outlet passage and being adapted to be deformed by the suction to thereby open the outlet passage, a flexible diaphragm secured in said casing and dividing the casing into a first chamber adjacent to said intake opening and a second chamber adjacent to said outlet opening, and an agitator member secured to said diaphragm and formed with an opening therethrough for the passage of air from said first chamber to said second chamber.

14. In a suction nozzle, a casing having an intake opening and having an outlet passage adapted to be connected to a source of suction, a pulsation member comprising resilient material secured to said casing and, in unstressed condition, sub-

stantially closing said outlet passage and being adapted to be deformed by the suction to thereby open the outlet passage, an agitator member within said casing adjacent to said intake opening, 5 resilient means for supporting said agitator member from said casing, and a flexible diaphragm between said agitator member and said casing dividing said casing into two chambers, said agitator member being formed with an opening therethrough for the passage of air from one chamber to the other.

15. In a suction nozzle, a hollow casing having edges defining an elongated intake opening, said casing formed with an outlet passage adapted to be connected to a source of suction, a pulsation member comprising resilient material secured to said casing and, in unstressed condition, substantially closing said outlet passage and being adapted to be deformed by the suction to thereby open 20 the said passage, an agitator member, said agitator member comprising an elongated bar formed with a recess in the lower side thereof and with an opening therethrough communicating with said recess, means for resiliently supporting said 25 agitator member longitudinally within said casing with the edges thereof bounding said recess adjacent to the plane of the edges defining said intake opening, and a flexible diaphragm between said agitator member and said casing dividing said casing into two chambers.

30. 16. In a suction nozzle, a hollow casing comprising an upper part and a lower part hinged together, the lower edge of said lower part defining an inlet opening, said upper part formed with an outlet opening adapted to be connected to a source of suction, a pulsation member secured within said upper part disposed in the path of air flow toward said outlet opening, said member being resilient and arranged to be vibrated by said air flow to thereby cause pulsations in the flow, a flexible diaphragm secured to said lower part, and an agitator member secured to the central part of said diaphragm and disposed adjacent to said intake opening.

45. 17. In a suction nozzle, a hollow casing having an intake opening, a flexible diaphragm secured within said casing, an agitator member secured to the central part of said diaphragm and formed with an opening therethrough, said diaphragm and said agitator member dividing the interior of said casing into a lower chamber adjacent to said intake opening and an upper chamber, said casing being formed with an outlet opening communicating with said upper chamber and adapted 50 to be connected to a source of suction, said casing being formed with an auxiliary inlet opening communicating with said upper chamber and with the atmosphere, and a pulsation member disposed in the path of air flow through said auxiliary inlet opening.

60. 18. In a suction nozzle, a hollow casing having an intake opening, a flexible diaphragm secured within said casing, an agitator member secured to the central part of said diaphragm and formed with an opening therethrough, said diaphragm and said agitator member dividing the interior

of said casing into a lower chamber adjacent to said intake opening and an upper chamber, said casing being formed with an outlet opening communicating with said upper chamber and adapted to be connected to a source of suction, said casing being formed with an auxiliary inlet opening communicating with said lower chamber and with the atmosphere, and a pulsation member disposed in the path of air flow through said auxiliary inlet opening.

5. 19. In a suction nozzle, a hollow casing having an inlet opening, a flexible diaphragm secured within said casing, an agitator member secured to the central part of said diaphragm and formed with an opening therethrough, said diaphragm and said agitator member dividing the interior of said casing into a lower chamber adjacent to said intake opening and an upper chamber, said casing being formed with an outlet opening communicating with said upper chamber and adapted to be connected to a source of suction, said casing being formed with an auxiliary inlet opening communicating with the interior of said casing and with the atmosphere, a first pulsation member disposed in the path of air flow through said auxiliary inlet opening, and a second pulsation member disposed in the path of air flow through said outlet opening.

15. 20. In a suction cleaning device, a hollow member having an intake opening and an opening adapted to be connected to a source of suction, an agitator member movably mounted with respect to said hollow member and movable due to variations of flow of air in said hollow member, and means separate from the agitator and located within said hollow member for producing said variations of flow of air in said hollow member to cause movement of said agitator member.

25. 21. In a suction cleaning device, a hollow member having an intake opening and an opening adapted to be connected to a source of suction, an agitator member movably mounted with respect to said hollow member and movable in a plurality of directions due to variations of flow of air flowing in one direction in said hollow member, and means separate from the agitator for producing said variations of flow of air in said hollow member to cause movement of said agitator member.

35. 22. In a suction cleaning device, a hollow member having an intake opening and an opening adapted to be connected to a source of suction, a movable diaphragm in said hollow member, an agitator member secured to said diaphragm and movable therewith, and means for varying the air pressure acting on said diaphragm to cause movement thereof.

45. 23. In a suction nozzle, a hollow member having an intake opening and an opening adapted to be connected to a source of suction, a movable diaphragm in said hollow member, an agitator member secured to said diaphragm and movable therewith, and means located within said hollow member for varying the air pressure acting on said diaphragm to cause movement thereof.

65. FREDRIK JOHAN ROBERT KARLSTRÖM.
